Primary Examiner — Jack Reickel*Assistant Examiner* — Bobby W Jones, II(74) *Attorney, Agent, or Firm* — Innovation Capital Law Group, LLP; Vic Lin(57) **CLAIM**

The ornamental design for a micro-nano bubble sprinkler, as shown and described.

DESCRIPTION

FIG. 1 is a front elevation view of a micro-nano bubble sprinkler, showing my design;

FIG. 2 is a rear elevation view thereof;

FIG. 3 is a right elevation view thereof;

FIG. 4 is a left elevation view thereof;

FIG. 5 is a top plan view thereof;

FIG. 6 is a bottom plan view thereof;

FIG. 7 is a front perspective view thereof; and,

FIG. 8 is a rear perspective view of thereof.

The broken lines in the FIGURES show portions of the micro-nano bubble sprinkler which form no part of the claimed design.

1 Claim, 8 Drawing Sheets(56)
